UNITED STATES PATENT OFFICE.

WILLIAM H. WINCHLER, OF ST. JOSEPH, MISSOURI.

PIN EXTRACTING AND REPLACING TOOL.

Application filed November 14, 1922. Serial No. 600,970.

To all whom it may concern:

Be it known that I, WILLIAM H. WINCHLER, a citizen of the United States, residing at St. Joseph, in the county of Buchanan and

5 State of Missouri, have invented certain new and useful Improvements in Pin Extracting and Replacing Tools, of which the following is a specification.

The present invention relates to tools for 10 extracting pins, such as those usually employed in valve stems for retaining the usual spring seat upon the stem, and has for the primary object thereof, the provision of such a device that is highly efficient of purpose, comparatively simple of construction, and inexpensive of manufacture.

With these general objects in view and others that will appear as the nature of the invention is better understood, the same 20 consists in the novel construction, combination, and arrangement of parts herein-after more fully described, illustrated in the accompanying drawings, and pointed out in the appended claim.

25 In the drawings forming a part of this application, and in which like designating characters refer to corresponding parts, through the several views:

Figure 1 is a plan view of the tool constructed in accordance with the present invention.

Figure 2 is a longitudinal sectional view upon the line 2—2 of Figure 1.

Figure 3 is a perspective view of the operating rod for controlling the movement of the grasping fingers of the tool.

Figure 4 is a view similar to Figure 1, but showing the pin engaging fingers tightly surrounding one end of a pin, and

40 Figure 5 is a cross sectional view on the line 5—5 of Figure 1.

Referring particularly to the drawings, my device comprises a relatively elongated tubular member 1, split at a point inwardly 45 of the outer end thereof as at 2. This split end of the tube provides relatively flat spring jaw members 3, which jaw members

are normally swung outward in a position as shown in Figure 1. The outer end of each of the jaw members are so formed as 50 to provide concavo-convex finger ends 4, the concaved surface of which are roughened at 5 as shown in Figure 2.

Upon the opposite end of the tube 1, there is positioned an open handle 6, which has 55 upon the front wall thereof, a sleeve adapted to engage over the end of the tube 1 to be there secured by rivets or the like 8. Slidably arranged within the tube 1, is an annular or other suitably shaped rod 9, the 60 forward end of which extends between the spring arms 3, and rigidly carries thereon an oblong plate 10. As in Figures 3 and 5, this plate has adjacent its opposite ends, vertical slots 11 for allowing the arms 3 to engage therethrough whereby any movement of the rod 9 within the tube will occasion a movement of the arms 3 toward or away from each other for similarly moving the pin grasping fingers 4.

Upon the upper side of the tube 1, and slightly forwardly of the sleeve 7 of the handle members 6, the said tube is slotted at 12 for receiving therethrough the shank 13 of an operating plate 14 upon or otherwise 75 secured adjacent the inner end of the rod 9, for permitting of movement of the rod within the tube 1 by the operator.

From the above description, it will be readily apparent that whenever it is desirable to remove the pin such as A in Figure 4, from the stem of a valve, the tool with the arms 3 open as in Figure 1 is brought into engagement with the pin A and the operator by sliding the rod 9 within the tube through 85 the instrumentality of the operating plate 14, slides the slotted plate 10 forwardly upon the arms 3 for consequently rigidly enclosing the curved fingers 4 upon the pin, whereby the same may be advantageously removed 90 from the valve stem.

While it is believed that from the foregoing description, the nature and advantages of the invention will be readily ap-

parent, I desire to have it understood that I do not limit myself to what is herein shown and described, and that such changes may be resorted to when desired as fall within the scope of what is claimed.

What I claim as new is:—

A device of the character described comprising a tube bifurcated at one end provided with a pair of grasping jaws and further provided with a slot at its upper end, a

rod slidable in the tube, an elongated plate carried by one end of the rod and slidably engaging the jaws, a laterally extending pin carried at one end of the rod and passing through the slot, and a grasping element 15 carried by the pin.

In testimony whereof I affix my signature.

WILLIAM H. WINCHLER.
